UNITED STATES PATENT OFFICE.

SIDNEY L. VAUGHAN, OF GRAND RAPIDS, MICHIGAN.

TICKET HOLDER AND CUTTER.

1,249,862.

Specification of Letters Patent. Patented Dec. 11, 1917.

Application filed May 10, 1917. Serial No. 167,740.

To all whom it may concern:

Be it known that I, SIDNEY L. VAUGHAN, a citizen of the United States of America, residing at Grand Rapids, in the county of 5 Kent and State of Michigan, have invented certain new and useful Improvements in Ticket Holders and Cutters; and I do hereby declare the following to be a full, clear, and exact description of the invention, such as 10 will enable others skilled in the art to which it appertains to make and use the same.

This invention relates to a ticket holder and cutter. It is the primary object and purpose of the invention to provide a holder 15 adapted to receive a block of tickets on which various characters indicative of cash fare collected are printed in a plurality of vertical columns, and to further provide the holder with an adjustable cutter member 20 which may be moved to a plurality of positions such that any character in any column may be selected and the ticket torn or cut across, one part of it showing by the highest character thereon the amount of fare paid, 25 while the other part is to be turned into the auditor's office and has all of the remaining and higher characters printed thereon. Many other objects and purposes together 30 with novel constructions by means of which the cutting member may be adjusted very simply and easily to a plurality of positions with respect to the ticket will more specifically appear from the following description of a preferred form of the device in which: 35 Figures 1, 2 and 3 are, respectively, front elevation, side view, and rear elevation of the ticket holder made in accordance with my invention and,

Figs. 4, 5, 6 and 7 are front elevations 40 showing the ticket holder applied to a block of tickets and with the movable cutter member adjusted to various positions for cutting the tickets at desired points.

Like reference characters refer to like 45 parts throughout the several views of the drawing.

The ticket holder is formed from sheet metal and includes in its construction a housing member having a front face 1 from each 50 side edge of which are bent backwardly extending sides 2, each turned in back of the face 1 to form bearing segments 3 as best shown in Fig. 3. Substantially at the center of the face 1 an irregular shaped opening is 55 made having two branches 4 and 5 with rounded ends located at an acute angle to

each other but joining and formed with a rounded upper end 6 as shown in the drawings. Back of the face 1 a plate 7 is mounted from which a stud 8 projects through said opening, there being a button 9 or the like fastened to the outer end of the stud and positioned over face 1 so that it may be engaged by the fingers to move the plate 7 to a number of positions. 65

Plate 7 is of special formation. It is narrower than the distance between the sides 2 and is of substantially rectangular outline except that its upper end is cut in a series of steps 10, 11 and 12 the edges of the plate at 70 such steps being formed with cutting edges. Also the upper edge of the face 1 is similarly formed with a cutting edge.

The housing member described is adapted to hold a plurality of tickets 6 which are 75 pressed against plate 7 by a plate 13 located loosely between sides 2 under the cutter plate 7 and at its ends extending a distance beyond each end of the housing face 1. The plate 13 has projections 14 at each side which come 80 just beyond the ends of the sides 2 of the housing precluding separation therefrom. At each end the plate 13 is curved to the rear to form rounded ends as indicated at 15, and leaf springs 16 are connected at one end to 85 one end of the plate 13 bearing at substantially their middle points against the in-turned ledges 3 of the housing and at their opposite ends slidably engaging against the opposite end of the plate 3 as shown. This 90 permits the insertion of a block of tickets between plate 13 and the cutter member 7 and as the tickets are removed one at a time, plate 13 moves more and more closely to the cutter member. The tickets indicated at 95 17 are of a width to pass freely between the sides 2 of the housing and are considerably longer than the housing or the plate 13 and at each end extend a distance beyond the ticket holder.

It is to be understood, however, that the construction of the ticket is in no way a feature of the present invention, it being the subject matter of a separate application for patent Ser. No. 167,811 filed May 10, 1917. It will be noted that on the tickets are printed four vertical columns of figures which are designed to include the various amounts of cash fare ordinarily collected by the conductor on an interurban railway. In practice these amounts may be made any desired amount to correspond to the various cash fares usually collected by 100 105 110

a conductor either on interurban or any other type of train. When a ticket is to be cut so that any selected amount appearing in the right hand vertical column is to be left, the 5 cutter plate occupies the position shown in Fig. 4 and the ticket is moved so that the proper amount shows just above the plate whereupon it may be cut along the cutting upper edge of the housing face 1. If an amount 10 in the second column from the right is to be indicated the cutter plate is moved with reference to the ticket substantially as shown in Fig. 5, the plate being partially cut along the upper edge of the housing 1 and the re- 15 mainder around the projection or step 10 of the cutter plate 7. For the third column from the right the cutter plate is moved to a position with reference to the ticket like that shown in Fig. 7, that is, the cutter 20 plate is moved over to the left from the position which it occupies in Fig. 5. And finally when the highest amount left is to be indicated in the fourth column the plate is moved upwardly with reference to the 25 housing and located on the ticket as shown in Fig. 6, so as to leave the highest character on the upper severed portion of the ticket in the left hand column.

This ticket holder and cutter is of very 30 simple construction and by means of a very simple adjustment of the cutting member may be used to divide tickets into two parts one of which will indicate the fare paid and adapted to be given to the passenger as a receipt 35 and also for use as a hat check, while the remaining portion of the ticket is retained by the conductor and turned into the auditor's office as usual. Some variations in minor detail of construction may be resorted to 40 without departing from my invention and I accordingly do not wish to be limited other than is necessitated by the claims which define the invention.

I claim:—

45 1. A device of the character described comprising a housing having a face plate, a cutter member located back of and in contact with the face plate, means for adjusting the cutter member lengthwise and transversely of the

face plate to a plurality of positions with 50 respect thereto, and means for yieldingly pressing a block of tickets against the cutter member, substantially as described.

2. A device of the character described comprising a housing having a face plate with an 55 opening therethrough, a cutter plate of less width than the face plate located back of said face plate, a pin in the cutter plate extending through the opening in the face plate, means connected to the pin adapted for manual operation to change the position of said cutter plate, and means for holding and yieldingly pressing tickets against said cutter plate.

3. A device of the character described comprising a housing having a face plate, a 65 cutter plate of less width than the face plate located back thereof, said cutter plate at one end being fashioned into a series of steps having cutting edges, and said face plate at its adjacent edge being also shaped to 70 form a cutting edge, means operable from in front of the face plate for changing and adjusting the position of the cutter plate with respect to said face plate, and means to press tickets against said cutter plate.

4. A device of the character described including a housing comprising a face plate, sides depending therefrom, and a ledge turned inwardly from each side, a cutter plate of less width than the face plate positioned directly back thereof, means operable from in front of the face plate for adjusting the cutter plate to a plurality of positions, a holder plate of substantially the same width as the distance between the sides of 85 the housing positioned back of the cutter plate, and spring means interposed between the holder plate and said ledges for yieldingly forcing said holder plate toward the 90 cutter plate.

5. A device as claimed in claim 4 in which said holder plate is longer than said cutter or face plates and extends a distance beyond each end thereof, and lateral stops on the holder plate at each end of the housing.

In testimony whereof I affix my signature.

SIDNEY L. VAUGHAN.
